Claims priority, application Sweden June 5, 1957

5 Claims. (Cl. 131—35)

This invention relates to the wrapping of cigar bunches and it is an object of the invention to make provisions for pasting the wrapper completely, or substantially completely, without unduly extending the path of travel of the wrapper carrier over means for transferring an adhesive to the wrapper supported by said carrier.

Another object of my invention consists in the provision of means for supplying the wrapper, supported by said carrier, with an adhesive before reaching the conventional wrapping mechanism and without any tendency of wrinkling, damaging and displacing the wrapper when supported by said carrier.

Still another object of my invention consists in the provision of a method and means for pasting the wrapper stepwise to cover the wrapper with complementary stripes or zones of an adhesive on minimizing the space required for that purpose.

Still another object of the invention consists in the provision of means enabling the use of different grades of adhesive for pasting different portions of the wrapper.

Still another object of the invention consists in the provision of separate wrapper pasting apparatus which can be replaced or cut out of operation if desired.

Still another object of the invention consists in the provision of a method and means for pasting the wrapper by consecutive steps between which the wrapper is subjected to a suction effect.

A further object of the invention consists in the provision of means especially well adapted for applying a long, narrow and distinct stripe of adhesive to a longitudinal edge portion of the wrapper.

With these and other objects, in view, the invention consists in certain constructions and combinations of parts which will be hereinafter fully described and set forth in the appended claims.

In the drawing:

Figure 1 is an elevational view of the portion of a cigar machine equipped with means embodying the invention;

Figure 2 is an elevational view, partly in section, taken on the line II—II of Figure 1;

Figure 3 is a plan view of a mechanism embodying the invention in which the wrapper carrier and its operating mechanism are indicated by full lines in a first paste receiving position and by chain-dotted lines in a second or subsequent paste receiving position; and

Figure 4 is a plan view showing means for controlling the wrapper carrier when moving past the first paste receiving position to the second paste receiving position.

Referring to the drawing, the wrapper carrier comprises a suction head 1 secured to a hollow spindle 6, the hollow spindle 6 in turn being rotatably mounted in the free end of a hollow arm 2. The suction head 1, the hollow spindle 6 and the hollow arm 2 communicate with each other interiorly thereof. The arm 2 is connected by a pivot 4 to another hollow arm 3 and communicates interiorly therewith. The arm 3 is secured

2

to a hollow vertical spindle 5 which is rotatably mounted in a hollow post 48 and communicates interiorly with said arm 3 and with a suction pump such as is shown in my U.S. Patent No. 2,379,575. To the carrier spindle 6 is secured an arm 7 which carries a roller 8 inserted in a groove 9 in a plate 11 secured to the machine frame 10. The spindle 6 carries a roller 12 which is inserted in a groove 13 in a plate 14 secured to the frame 10. To the spindle 5 is secured a toothed segment 15 which meshes with a rack bar 16 which is slidably mounted in a rectilinear guide-way 17 fixed to the machine frame. The rack bar 16 is by a pin 18 pivotally connected to one end of a rod 19. The other end of the rod 19 is by a pin 20 pivotally connected to one arm 21 of a bell crank lever secured to a rocking shaft 22 rotatably mounted in the machine frame. The other arm 23 of the bell crank lever carries a roller 24 which is inserted in a curved groove 25 in a face cam 26 secured to the drive shaft 27.

20 By the mechanism and control means as described herewith the wrapper carrier in the form of suction head 1 will be reciprocated periodically in a curved path between a conventional stationary wrapper cutting bed 28 fixed to the frame 10 and a replaceable paste supplying apparatus 29 whereby it moves over the conventional cigar wrapping mechanism 30 mounted on the frame 10. The wrapping mechanism 30 and wrapper cutting means may be of any well known construction, such as shown in my Patents Nos. 2,267,648 and 2,539,034, respectively.

The wrapper is transferred from the cutting bed 28 to the wrapping mechanism 30 by the suction head 1 and the suction head is guided by the groove 13 so that it will move in a definite curved path simultaneously as it is controlled by the guide groove 9 so as to be rotated about the center of its spindle 6 in a definite manner simultaneously as the suction effect in the carrier is controlled by conventional means such as that shown in my Patent No. 2,379,575.

40 Between the cutting bed 28 and the wrapping mechanism 30 is disposed a replaceable pasting apparatus 31 which comprises a rigid paste transferring arm 33 which is adapted to move up and down in a paste container 32. The arm 33 has a relatively long horizontally projecting end 34 bent angularly to conform with the contour of a longitudinal edge of the suction head 1. The arm 33 is secured to a vertical rod 35 which is slidably mounted in a bracket 36 fixed to a channel iron 37 rigidly mounted on the machine frame 10. At its 50 bottom end the rod 35 is by a pin 38 pivotally connected to the upper end of another rod 39 the bottom end of which is, by a pin 40, pivotally connected to an arm 41 secured to the rocking shaft 22. The arm 41 carries a follower 42 inserted in the groove 43 of a face cam 44 secured to the drive shaft 27. The paste supplying apparatus 29 disposed on the further side of the wrapping mechanism 30 is of substantially the same construction as the paste supplying apparatus 31. It has a paste container 45 and a paste supplying arm 46 which is secured to a vertical rod 47 operated by a face cam 48 (not shown) which is secured to the shaft 27 and is similar to the face cam 44 but displaced angularly relative to the latter.

65 During each cycle of operation of the machine the suction head 1 transfers a cut wrapper from the cutting bed 28 to the wrapping mechanism 30. The groove 25 of the cam 26 has such a curvature that the suction head 1 will during its travel towards the wrapping mechanism 30 be arrested for a very short period above the pasting apparatus 31. Simultaneously the paste supplying arm 33 is elevated so that it will by its end portion 34 apply a narrow definitely shaped angular stripe of adhesive of

substantial length to one of the edges of the wrapper supported by the carrier 1. Thereby said edge of the wrapper will be pasted practically all the way from its tuck end, at T, to a point at a desired distance from the head end, at S. After the short rest in the position M (Figure 4) above the pasting apparatus 31 the suction head will reassume its travel in the direction towards its turning point at E in which the head 1 supports the tuck end of the wrapper in a position above the wrapping mechanism 30 so that said tuck end will be accessible to the conventional tucking needle, e.g. as shown in U.S. Patent No. 2,754,481 adapted to catch and move said tuck end down against the cigar bunch enclosed in the wrapping when said mechanism starts its operation. Simultaneously as the tuck needle applies the tuck end of the wrapper to the tuck end of the bunch the paste supplying arm 46 is elevated and applies to one edge of the wrapper a relatively thin and short stripe of adhesive which will form a continuation of the relatively long and narrow adhesive stripe primarily applied by the arm 33 and extends on to the flag or head end S of the wrapper. Thereby the wrapper has been provided with a narrow and distinct adhesive stripe extending continuously or stepwise, all along the wrapper or at least approximately from one end of the wrapper to its other end and this result will be obtained without extending the path of travel of the suction head and increasing the space, without any appreciable prolongation of the operating cycle and without the use of any large paste applying member. The paste supplying 31 might, if desired, be cut out of operation, e.g. by removing its paste transferring arm 33. The pasting apparatus 29 and 31 can hold paste of different grades if desired.

It will be understood that I do not care to limit the scope of the invention to any particular form of the cigar and wrapper. Thus the terms "head end" and "tuck end" as used hereinbefore are merely illustrative and not intended to denote any particular form or use.

I claim:

1. In a cigar wrapping machine, a wrapper carrier, wrapper cutting means, a cigar wrapping mechanism spaced from said wrapper cutting means, means for moving said wrapper carrier from said cutting means to said wrapping means to transfer a wrapper from said cutting means to said wrapping mechanism, and pasting means disposed on opposite sides of said wrapping mechanism for applying adhesive to different portions of the wrapper supported by said carrier.

2. In a cigar wrapping machine, a wrapper carrier, wrapper cutting means, a cigar wrapping mechanism spaced from said wrapper cutting means, means for moving said wrapper carrier from said cutting means past said wrapping mechanism to a turning point and returning said carrier for applying the wrapper to a cigar bunch in said wrapping mechanism, pasting means disposed at said turning point to apply an adhesive to one portion of the wrapper supported by said carrier, and a pasting apparatus disposed between said wrapper cutting means and said wrapping means to apply an adhesive to another portion of the wrapper supported by said carrier.

3. In a cigar wrapping machine, a wrapper carrier,

wrapper cutting means, a cigar wrapping mechanism spaced from said wrapper cutting means, means for moving said wrapper carrier from said cutting means past said wrapping mechanism to a turning point and returning said carrier for applying the wrapper to a cigar bunch in said wrapping mechanism, pasting means disposed at said turning point to apply a relatively short stripe of adhesive to one portion of the wrapper supported by said carrier, and a pasting apparatus disposed between said wrapper cutting means and said wrapping means to apply a relatively long complementary stripe of adhesive to another portion of the wrapper supported by said carrier.

4. In a cigar wrapping machine, a wrapper carrier, wrapper cutting means, a cigar wrapping mechanism spaced from said wrapper cutting means, a first wrapper pasting means disposed between said cutting means and said wrapping means and comprising a paste supplying member and means for controlling said member, a second wrapper pasting means disposed on the side of said wrapping mechanism opposite said first pasting means, means for moving said wrapper carrier from said cutting means and past said wrapping mechanism to a turning point at said second pasting means for applying adhesive to a portion of the wrapper supported by said carrier, and returning said carrier to apply the wrapper to a bunch in said wrapping mechanism, means for intermittently arresting said carrier in a position opposite to said first pasting mechanism, and means operatively connected with said arresting means to move said paste supplying member towards said carrier to apply an adhesive to another portion of the wrapper supported by said carrier at rest.

5. In a cigar wrapping machine, a wrapper carrier, wrapper cutting means, a cigar wrapping mechanism spaced from said wrapper cutting means, a first wrapper pasting means disposed between said cutting means and said wrapping means and comprising a substantially rigid paste supplying member and means for controlling said member, a second wrapper pasting means disposed on the side of said wrapping mechanism opposite said first pasting means, means for moving said wrapper carrier from said cutting means and past said wrapping mechanism to a turning point at said second pasting means for applying adhesive to a portion of the wrapper supported by said carrier, and returning said carrier to apply the wrapper to a bunch in said wrapping mechanism, means for intermittently arresting said carrier in a position opposite to said first pasting mechanism, and means operatively connected with said arresting means to move said paste supplying member towards said carrier to apply an adhesive to another portion of the wrapper supported by said carrier at rest.
